SHOCK-ABSORBENT MOUNTING

Eugenio J. Lombardi, Richmond Hill, N. Y., assignor to Federal Telephone and Radio Corporation, Newark, N. J., a corporation of Delaware

Application May 24, 1943, Serial No. 488,115

11 Claims. (Cl. 248—358)

The present invention relates to mountings, and more particularly to a shock-absorbent mounting for electrical apparatus which maintains the apparatus in a desirable position and at the same time permits ready access for purposes of adjustment or repair.

When a cathode-ray oscilloscope of the type used for direction finding is employed on a warship, particular care must be taken to cushion the oscilloscope against the severe shocks that result from firing of the guns or from other causes incident to the operation of the ship.

Considerable difficulty has been encountered in designing a mounting for such an oscilloscope with regard to the particular construction of its resilient members so as to provide maximum cushioning of the oscilloscope. This is particularly so since the permissible displacement of the oscilloscope is also strictly limited. These resilient members must provide cushioning from shocks applied to the mounting from all possible directions including the vertical. Furthermore, such resilient members must be quickly demountable so that the oscilloscope can be disconnected from the mounting with a minimum of delay for purposes of replacement or repair.

Accordingly one object of the present invention is to provide, as a part of a mounting for an oscilloscope or other similar instrument, resilient supports that will absorb shocks received by the mounting from any direction.

A further object of the invention is to provide means whereby any portion of the oscilloscope or similar assembly may be easily reached for adjustment or repair without the necessity of removing the assembly from the mounting.

An additional object of the invention is to provide a pivoted shock-absorbent support for an electrical apparatus so that the position of the apparatus in the mounting may be altered without disconnecting the pivoted support.

Another object of the invention is to reduce oscillation effects between an electrical assembly and its mounting by positioning all of the resilient supports for the assembly in the same plane.

Still another object of the invention is to provide, in a mounting for electrical apparatus, resilient supporting members for the apparatus which are readily demountable to permit rapid disconnection of the apparatus from the mounting.

Further objects and advantages of the invention will be apparent from the following description of an embodiment of one form of the inven-

tion and from the accompanying drawings, in which:

Fig. 1 is a view of a mounting saddle for an oscilloscope assembly in accordance with the present invention, also showing the assembly in outline;

Fig. 2 is a side view of a mounting for the apparatus of Fig. 1, also showing the assembly of Fig. 1 in outline;

Fig. 3 is a front view of Fig. 2;

Figs. 4 and 5 are detailed views of parts of Fig. 2.

In Fig. 1 is shown a tubular saddle 6 rigidly positioning a cathode-ray oscilloscope assembly 8. Formed on the saddle 6 are two fingers or lugs 7 each having an opening 7A therein, and two fingers or lugs 7' each having an opening 7'A therein as illustrated.

Since the particular construction of the oscilloscope assembly 8 forms no part of the present invention it is shown in outline to simplify the drawings.

In Figs. 2 and 3 is shown a mounting framework 9 supporting a control panel 9A. From the upper portion of the framework 9 two columns 13 extend downwardly as shown. Rigidly attached to the framework 9 and the columns 13 are two horizontal plates 9B. A pair of bracket supports 18 are secured to the plates 9B by means such as the nuts 18A and studs 18B. Secured to the bracket supports 18 by means such as the bolts 16 are a pair of U-shaped brackets 15. The two upper fingers 7 of the saddle 6 enter these brackets 15 in a manner hereinafter to be described.

Tubular members 9C and 9D constitute a part of the lower portion of the framework 9. Clamped near the ends of these tubular members 9C and 9D by means such as the bolts 10A and 10B (Fig. 5) are two shells 10. These shells 10 rotatably journal a tubular member 11 which extends parallel to the tubular members 9C and 9D as shown in Fig. 3. A removable bolt 42 in each shell 10 when in place holds the tubular member 11 from rotating within the shells 10.

Rigidly attached to the tubular member 11 are two bracket supports 19 to which two U-shaped brackets 15' are secured as by four bolts 16. The lower fingers 7' of the saddle 6 enter these brackets 15' in a manner best shown in Fig. 5.

The oscilloscope assembly 8 positioned in its saddle 6 is mounted in the position shown in Figs. 2 and 3. The four brackets 15, 15' are in the same common slanting plane and the assembly is tilted at the angle best shown in Fig. 2. By re-

moving the nuts 18A securing the bracket supports 18 to the plates 9B, the upper part of the saddle 6 can be disconnected from the framework 9, and if the pins 12 are also removed the saddle 6 can be lowered to an approximately horizontal position through rotation of the tubular member 11. Means such as a chain 9E may be used to limit the extent of such rotation.

Through the above mode of operation, easy access for inspection or adjustment of the oscilloscope assembly 8 can be made without disconnecting the lower brackets 15' or removing the saddle 6 from the framework 9.

Coming now to the particular shock-absorbent features of the invention, Figs. 4 and 5 show detailed views of the resilient mountings of Fig. 2.

Referring first to Fig. 4, the U-shaped bracket 15 is secured by means of the bolts 16 to the bracket support 18 in turn bolted at 18A to the plate 9B as hereinbefore described.

From Fig. 1 it is seen that each of the two fingers 7 has an opening 7A therein. One of the fingers 7 is inserted in the U-shaped bracket 15 of Fig. 4 so that the opening 7A in finger 7 is within the bracket.

A cylindrical block 20 of rubber or other resilient material has securely attached thereto two metal discs 25 and 26, said discs being disposed on opposite faces of the block 20 as shown. Each of these discs has an extending threaded portion 21 and 22 respectively. The portion 22 extends through an opening in the bracket 15, and a nut 24 threadably engaging the portion 22 holds the plate 26 in position relative to the bracket 15. The other extending portion 21 passes through the opening 7A in finger 7, and a nut 23 threadably engaging the portion 21 holds the finger 7 in position relative to the disc 25. A ring 28 of rubber or other resilient material encloses the sides of nut 23, and separates the top of finger 7 from the lower surface of bracket support 18.

A recess 27 above the nut 23 allows for upward movement of the nut relative to the support 18. A space 29 between the resilient members 20 and 28 and the interior walls of bracket 15 and support 18, respectively, allows for any lateral displacement of the resilient members with respect to the bracket and support resulting from horizontal shocks applied to the block 20 through the bracket 15.

In Fig. 5 is shown the lower mounting of Fig. 2. The rotatable tubular member 11 (which is journaled in the shell 10) has rigidly attached thereto two bracket supports 19 (Fig. 3). Each bracket support 19 has a U-shaped bracket 15' secured thereto by means such as the bolts 16'.

A cylindrical block 20' of rubber or other resilient material has two metal discs 25' and 26' attached to the opposite faces thereof, in a manner similar to block 20 of Fig. 4. A threaded extending portion 22' on disc 26' extends through an opening in bracket support 19 and into threaded engagement with an opening in rotatable tube 11 as shown in Fig. 5. When the disc 26' is tightened it results in a rigid positioning of resilient block 20', disc 26', bracket support 19, and tubular member 11, so that rotation of the last-named member will rotate all of these elements as a unit.

The upper disc 25' on resilient block 20' has an extending threaded portion 21' passing through one of the openings 1'A in fingers 1'. A nut 23' threadably engaging the threaded portion 21' holds the finger 1' in position relative to the disc 25'. A ring 28' of rubber or other resilient ma-

terial encloses the sides of nut 23' and separates the top of finger 1' from the top inner surface of bracket 15', thus acting to cushion a downward shock applied to the bracket 15'. To allow for the upward displacement of ring 28' due to such a shock, the top of bracket 15' is partially cut away above the nut 23' as shown at 27'. A space 29' between the inner side walls of bracket 15' and resilient blocks 20' and 28' allows for the lateral displacement of such blocks due to horizontal forces applied to the bracket 15'.

Thus it will be seen that the saddle 6 actually "floats" on the resilient blocks 20, 20'. No rigid connection exists between the saddle 6 and the framework 9. The four supporting blocks 20, 20' are positioned in the same plane to minimize oscillatory effects. In addition, downward shocks are cushioned by the supplemental resilient blocks 28, 28'. Furthermore the supporting elements are simple in design and readily replaceable, while many of the individual parts of the upper and lower mountings are interchangeable.

While I have described above the principles of my invention in connection with specific apparatus, and particular modifications thereof, it is to be clearly understood that this description is made only by way of example and not as a limitation on the scope of my invention as set forth in the objects of my invention and the accompanying claims.

I claim:

1. In a shock-absorbent device for electrical apparatus, a saddle for the apparatus, a mounting, a pair of resilient members, a pair of extending portions on said saddle, means for respectively supporting one side of each of said extending portions by said resilient members, a pair of brackets respectively partially enclosing said resilient members, and a pair of bracket supports rotatably attached to said mounting and supporting and positioning said brackets and said resilient members.

2. In a shock-absorbent device for electrical apparatus, a framework, a shell rigidly secured to said framework and having an opening therein, a tubular member rotatably journaled by said shell and having an opening therein, a bracket support rigidly attached to said tubular member, a resilient member supported by said bracket support, and a bolt removably insertable through the openings of said shell and said tubular member to selectively control the rotation of said tubular member with respect to said shell.

3. A device according to claim 2, further comprising a saddle for the apparatus, and an extending portion on said saddle designed to be supported by said resilient member.

4. A device according to claim 2, further comprising a saddle for the apparatus, an extending portion on said saddle supported on one side by said resilient member, a bracket secured to said bracket support and partially enclosing said resilient member, and a second resilient member within said bracket, on the opposite side of said extending portion from said first mentioned resilient member, and between said extending portion and the inner wall of said bracket extending parallel to said bracket support.

5. In a device for protecting an apparatus from shocks, a mounting having a threaded opening therein, a bracket support supported by said mounting, said bracket support having an opening therein, a resilient member on said bracket support, positioning means attached to said resilient member and having an extending thread-

ed portion, said extending threaded portion designed to pass through the opening in said bracket support to threadably engage the threaded opening of said mounting, an extending portion on said apparatus having an opening therein, a second positioning means attached to said resilient member and oppositely disposed to said first-mentioned positioning means, said second positioning means having an extending threaded portion, said extending threaded portion of said second positioning means designed to pass through the opening in the extending portion on said apparatus, and a nut threadably engaging the extending threaded portion of said second positioning means to position said extending portion on said apparatus with respect to said second positioning means.

6. A device according to claim 5 wherein said bracket support is rotatably supported by said mounting.

7. In a shock-absorbent device for an apparatus, a mounting, a bracket support on said mounting, a bracket secured to said support, a resilient member within said bracket and supported by said bracket, an extending portion on said apparatus, means for positioning and supporting one side of said extending portion on said resilient member, a second resilient member on the opposite side of said extending portion from said first-mentioned resilient member and between said extending portion and said bracket support, so that selective displacement of said extending portion with respect to said bracket and said bracket support will compress one of said resilient members between said extending portion and selectively said bracket and said bracket support, said bracket support having a recess therein to permit compression thereinto of a portion of said second resilient member upon selective movement of said extending portion relative to said bracket and said bracket support.

8. In a shock-absorbent device for electrical apparatus, a mounting, a supporting and housing

structure having two elements, a bracket and its support, a resilient member secured to one of said elements and within said bracket, an extending portion on said apparatus, means for positioning one side of said extending portion on said resilient member, and a second resilient member on the opposite side of said extending portion from said first-mentioned resilient member and within said structure, so that selective displacement of said extending portion with respect to said bracket and said bracket support will compress one of said resilient members between said extending portion and selectively said bracket and said bracket support.

15 9. A device according to claim 8, comprising additional selectively adjustable means for positioning the bracket support relative to said mounting, so that said adjustable means may be maintained in fixed condition during desired periods and maintained in adjustable condition during other desired periods.

20 10. In a shock-absorbent device for electrical apparatus, a mounting, two pairs of resilient members on said mounting for supporting said apparatus, one of said pairs of resilient members being demountably attached to the upper portion of said mounting, and the other of said pairs of resilient members being rotatably attached to the lower portion of said mounting, both of said pairs of resilient members being generally rectangularly disposed in the same plane.

25 11. In a shock-absorbent device, a saddle for the apparatus to be carried and provided with extending portions, mounting units each including as elements a bracket and a support therefor, a resilient member carried by one of said elements and within the bracket, means whereby one side of each extending portion is carried by said resilient member, and a second resilient member within each unit and positioned between the opposite side of the said extending portion and the other of said elements.

EUGENE J. LOMBARDI.
